HANGER FOR WALKING BEAMS

Dee E. Humphrey, Dallas, Tex., assignor to
Welded Tank and Steel Company, Inc., Dallas,
Tex., a corporation of Texas

Application December 26, 1934, Serial No. 759,194

13 Claims. (Cl. 74—41)

This invention relates to new and useful improvements in walking beams.

One object of the invention is to provide an improved walking beam having hangers for connection with the usual polish rod and pitman.

5 An important object of the invention is to provide a hanger for a walking beam arranged to be fastened to said beam and having its end projecting beyond the end of the beam, whereby bearing supports for a polish rod or a pitman may be 10 mounted thereon.

Another object of the invention is to provide a hanger for a walking beam comprising a pair of angular members engaging over the base flange 15 of the beam and secured thereto at the end of said beam, said members being spaced apart by the web of the beam so that a rod supported by the hanger may depend between the members.

Still another object of the invention is to provide 20 an improved walking beam which is provided with top and bottom reinforcing plates at its central portion, each plate having openings therein spaced along its longitudinal axis, whereby welding or other material may be inserted in said openings to rigidly secure the plates to the beam.

25 A further object of the invention is to provide a plurality of vertical braces which are secured to the web and flanges of an I-beam and which extend between the flanges of said beam, whereby 30 the rigidity and strength of said beam is greatly increased.

A construction designed to carry out the invention will be hereinafter described, together with other features of the invention.

35 The invention will be more readily understood from a reading of the following specification and by reference to the accompanying drawings, in which an example of the invention is shown, and wherein:

40 Figure 1 is a side elevation of a walking beam mounted on a Samson post and constructed in accordance with the invention.

Figure 2 is a transverse vertical sectional view taken on the line 2—2 of Figure 1.

45 Figure 3 is a plan view of the beam and having part thereof broken away to show one of the hangers which are secured thereto.

Figure 4 is a longitudinal, vertical sectional view 50 of the parts shown in Figure 3.

Figure 5 is a transverse, vertical sectional view, taken on the line 5—5 of Figure 3.

Figure 6 is a vertical sectional view taken on the line 6—6 of Figure 1.

55 Figure 7 is an isometric view of one of the

hangers fastened on the end of the beam, which is broken away.

Figure 8 is a side elevation of a short piece of I-beam of which the brace members are formed.

Figure 9 is a side elevation of another form of 5 I-beam,

Figure 10 is an isometrical, sectional view of the same,

Figure 11 is a transverse, vertical sectional view, taken on the line 11—11 of Figure 10.

In the drawings the numeral 10 designates an upright Samson post which may be of any suitable type. The type shown comprises four legs 11 converging upwardly to form a pyramid. The usual bearing saddle 12 is mounted on the upper 15 end of the post and receives the transverse fulcrum bar or rocker 13 of a walking beam 14.

The walking beam is preferably formed of an I-beam 15 which has its central portion reinforced by longitudinal plates or bars 16. The plates lie 20 along the top and bottom of the beam and are provided with a plurality of elongated openings 17 extending therethrough. The openings are positioned along the longitudinal axis of each plate and when said plate is in position on the 25 beam, these openings are in alignment with the vertical web 15' of said beam.

Welding, or other suitable material 18 is inserted in the openings and it is obvious that since the openings are directly above the web, each 30 plate is secured by the welding to said web. If desired, each plate may be further welded to the beam along its edges. By providing the openings 17, it will be seen that the plates become a part of the web of the beam and are not secured only to 35 the flanges, as is the usual practice. The beam is reinforced and its strength greatly increased without the addition of a great deal to its weight.

To further brace the beam at its central portion, vertical braces 19 extend between the flanges 40 of the beam on each side of the web. The braces may be positioned at any points near the center of the beam and are preferably welded thereto so as to provide an integral structure. It is pointed out that the rigidity of the beam is greatly increased and by providing both bars 16 and braces 45 19, a beam of lighter weight which can withstand greatly increased loads is formed.

On each end of the beam a hanger is provided. Each hanger comprises a pair of angular brackets 50 or members 21 disposed longitudinally of the beam and extending beyond the end thereof. Each bracket has its horizontal member overlying the base flange of the beam 14 and abutting the web thereof. The vertical member depends from the 55

horizontal member contiguous to the base flange of the beam. I have shown the horizontal member welded to the web and the vertical member welded to the base flange, but the angular brackets 5 may be fastened in any desired manner, although welding has been found satisfactory.

Vertical braces 20, similar to the braces 19, are mounted between the underside of the top flange of the beam and the top of the inner end of each 10 bracket on each side of the web. These braces are preferably welded to the brackets, web, and top flange, and it is obvious that when a load is placed on the outer end of the brackets, the braces 20 will prevent such load from breaking the weld 15 and jerking the brackets from the beam.

On the projecting end of each hanger are mounted bearing boxes 22. One of these boxes has the upper end of the polish rod 23 journaled 20 therein. The other box carries the ordinary operating pitman 24 for imparting motion from the power source (not shown) to the walking beam in the usual manner. It is pointed out that the web of the beam spaces the brackets sufficiently 25 far apart to allow the pitman and polish rod to depend therethrough and to freely swing therein. It will be seen that a very efficient, simple and strong hanger is thus formed. It is pointed out that any suitable means for carrying the pitman and rod may be used on the hanger. The brackets 30 being merely a pair of angular members, are very cheap, and by welding said members to the walking beam and bracing their inner ends with the braces 20, a sturdy support for the pitman and rod is provided.

35 The Sampson post is provided with the customary headache post 25 on one side and the ordinary ladder 26 on the other. At the lower end of the legs, I provide foot plates or members 27. These plates have a tendency to work or breathe 40 during the swinging of the beam, due to the load carried by the polish rod. For overcoming this breathing, I weld triangular brace members 28 to the plates and to the lower portion of the legs. These members may be formed by cutting a short 45 piece of I-beam A diagonally, as shown in dotted lines in Figure 8.

It will be seen that the angular brackets which form each hanger are nothing more than short pieces of angle bars and a very cheap and inexpensive structure is had. The welding of the longitudinal bars 16 and the hanger to the walking beam, as well as the welding of the braces 19 and 20 between the flange of the beam make for easy and quick assembling of the parts, and also 55 provide a positive fastening means for the same. It is again pointed out, however, that the invention is not to be limited to welding, as satisfactory results may be obtained with other fastenings.

60 In Figures 9 to 11 I have shown another form of walking beam 30. This beam is constructed of a central longitudinal bar 31 which forms the web of the beam. A pair of longitudinal, angular members 32 are secured at the upper and lower 65 ends of the bar and each member has its vertical leg 33 contiguous to the bar and its horizontal leg 34 extending outwardly therefrom, whereby an I-beam is formed, as shown in Figures 10 and 11. The flat outer side of the horizontal legs 70 34 of the angular members is slightly beyond each edge of the central bar 31, whereby a central longitudinal groove 35 is formed in the upper and lower ends of the I-beam.

Thus when the reinforcing plates 16 are placed 75 on the top and bottom of the beam, the openings

17 in the plates will be in alinement with the groove 17. The insertion of welding 18 through the openings 17 will enter the groove, and it is obvious that an integral structure of the plates and the beam is produced, whereby the plates and beam are permanently secured together. 5

What I claim and desire to secure by Letters Patent, is:

1. A walking beam comprising, a swinging member having upper and lower horizontal flanges connected by a vertical web and arranged to be mounted on a Sampson post, longitudinal plates disposed along the top and bottom of said member for reinforcing the central portion thereof and having openings therein, the openings of 15 the plates being in alinement with the web of the member when the plates are in position on said member, and means inserted in the openings of said plates and secured to the member, whereby the plates are rigidly secured to said member. 20

2. A walking beam comprising, a swinging member, longitudinal plates having openings therethrough along their longitudinal axis and arranged to lie along the top and bottom of the member at the central portion thereof to reinforce said member, and means inserted in the openings of said plates and secured to said member for fastening the plates to said member. 25

3. A walking beam comprising, a swinging member having upper and lower horizontal flanges connected by a vertical web and arranged to be mounted on a Sampson post, longitudinal plates disposed along the top and bottom of said member for reinforcing the central portion thereof and having openings therein, the openings of 30 the plates being in alinement with the web of the member when the plates are in position on said member, means inserted in the openings of said plates and secured to the member, whereby the plates are rigidly secured to said member, 35 and vertical braces extending between the flanges of the member on each side of the web for further bracing the central portion of the beam. 40

4. A walking beam comprising, a swinging member having upper and lower horizontal flanges connected by a vertical web and arranged to be mounted on a Sampson post, longitudinal plates disposed along the top and bottom of said member for reinforcing the central portion thereof and having openings therein, the openings of the plates being in alinement with the web of the member when the plates are in position on said member, means inserted in the openings of said plates and secured to the member, whereby the plates are rigidly secured to said member, and a pair of angular brackets secured to said member and projecting beyond the end thereof for supporting a vertical rod. 45

5. A walking beam comprising, a swinging member having upper and lower horizontal flanges 60 connected by a vertical web and arranged to be mounted on a Sampson post, longitudinal plates disposed along the top and bottom of said member for reinforcing the central portion thereof and having openings therein, the openings of the plates being in alinement with the web of the member when the plates are in position on said member, means inserted in the openings of said plates and secured to the member, whereby the plates are rigidly secured to said member, a pair 65 of angular brackets secured to said member and projecting beyond the end thereof for supporting a vertical rod, and a vertical brace extending between the underside of the top flange of the beam 70 75

and the top of the inner end of each bracket for bracing each bracket.

6. A walking beam comprising, a swinging member having upper and lower horizontal flanges connected by a vertical web and arranged to be mounted on a Samson post, longitudinal plates disposed along the top and bottom of said member for reinforcing the central portion thereof and having openings therein, the openings of the plates being in alignment with the web of the member when the plates are in position on said member, means inserted in the openings of said plates and secured to the member, whereby the plates are rigidly secured to said member, a pair of angular brackets, each bracket overlying the base flange of said member, the other side of each bracket depending downwardly contiguous to the edge of said base flange, and means for securing each bracket to the end of the base flange, where- 20 by the same projects beyond the edge of said base flange.

7. A walking beam comprising, an I-beam, a pair of elongate angular brackets, each bracket having its horizontal member secured to the base flange and extending a substantial distance therealong and also having aprons depending contiguous to the edge of the base flange, said brackets extending beyond the end of the beam so that a vertical rod supported thereon may depend there- 30 from, and vertical braces, each extending on one side of the web of the beam from the inner end of each bracket to the underside of the top flange of the I-beam for reinforcing and bracing each bracket.

8. A walking beam comprising, an I-beam, longitudinal plates having openings therethrough formed along the longitudinal axis of said plates and arranged to be placed on the top and bottom of said beam at its central portion for reinforcing the beam, means inserted in the openings for fastening the plates to the beam, and a pair of angular brackets, each bracket having one side secured to the base flange of the beam and also having aprons depending contiguous to the edge of said base flange, said brackets extending beyond the end of the beam so that a vertical rod supported thereon may depend therefrom.

9. A walking beam comprising, an elongated vertical bar, a pair of elongated angular members secured to the upper and lower marginal portions of the bar, each angular bracket having its vertical leg contiguous and secured to said marginal portion and having its horizontal leg directed outwardly, whereby a base and top flange is formed on the vertical bar, the outer sides of the horizontal legs of the brackets extending beyond the upper and lower edges of the bar, whereby a central longitudinal groove is provided in the beam, longitudinal plates having openings therein arranged to be placed on the top and bottom of said beam at its central portion for reinforcing said beam, said openings being in alignment with the groove in the beam when the plates are in position on said beam, and means inserted in the openings and groove for fastening said plates to the beam.

10. A walking beam comprising, an elongated vertical bar, a pair of elongated angular members secured to the upper and lower marginal portions of the bar, each angular bracket having its vertical leg contiguous and secured to said marginal portion and having its horizontal leg directed

outwardly, whereby a base and top flange is formed on the vertical bar, the outer sides of the horizontal legs of the brackets extending beyond the upper and lower edges of the bar, whereby a central longitudinal groove is provided in the beam, longitudinal plates having openings therein arranged to be placed on the top and bottom of said beam at its central portion for reinforcing said beam, said openings being in alignment with the groove in the beam when the plates are in position on said beam, means inserted in the openings and groove for fastening said plates to the beam, and a pair of angular brackets at each end of said beam and secured thereto, the brackets projecting beyond the end of said beam for supporting a vertical rod.

11. A walking beam comprising, an elongated vertical bar, a pair of elongated angular members secured to the upper and lower marginal portions of the bar, each angular bracket having its vertical leg contiguous and secured to said marginal portion and having its horizontal leg directed outwardly, whereby a base and top flange is formed on the vertical bar, the outer sides of the horizontal legs of the brackets extending beyond the upper and lower edges of the bar, whereby a central longitudinal groove is provided in the beam, longitudinal plates having openings therein arranged to be placed on the top and bottom of said beam at its central portion for reinforcing said beam, said openings being in alignment with the groove in the beam when the plates are in position on said beam, means inserted in the openings and groove for fastening said plates to the beam, a pair of angular brackets at each end of said beam and secured thereto, the brackets projecting beyond the end of said beam for supporting a vertical rod, and a vertical brace extending between the inner end of each bracket and the underside of the top flange of said beam for bracing said bracket.

12. The method of reinforcing a swinging walking beam for mounting on a Samson post or the like, comprising, a swinging member having upper and lower horizontal flanges connected by a vertical web consisting in disposing longitudinal plates having a central series of openings therethrough along the top and bottom of said member so that the openings of the plates are in alignment with the web of the member, and inserting in the openings of said plates metallic securing means integrally uniting the plates to said member whereby the plates are rigidly secured to said member.

13. The method of reinforcing a swinging walking beam for mounting on a Samson post or the like, comprising, a swinging member having upper and lower horizontal flanges connected by a vertical web and openings in the flanges in line with the web, consisting in disposing longitudinal plates having a central series of openings therethrough along the top and bottom of said member so that the openings of the plates are in alignment with the web of the member and cooperating with the openings in the flanges there- 60 of, and inserting in the openings of said plates and flanges of the beam member metallic securing means integrally uniting the plates to said member whereby the plates are rigidly secured to said member.

DEE E. HUMPHREY.
